UNITED STATES PATENT OFFICE.

CHARLES J. CONSER, OF CHICAGO, ILLINOIS.

DESIGN FOR A BED-SOFA.

SPECIFICATION forming part of Design No. 22,922, dated November 28, 1893.

Application filed October 23, 1893. Serial No. 488,955. Term of patent 7 years.

To all whom it may concern:

Be it known that I, CHARLES J. CONSER, a citizen of the United States, residing at Chicago, in the county of Cook and State of Illinois, have invented and produced a new and original Design for Bed-Sofas or Folding Beds, of which the following is a full, clear, and exact specification, reference being had to the accompanying drawing, showing a part thereof.

The said drawing is a perspective view of a bed sofa or folding-bed embodying my design, showing the same in its extended or unfolded condition.

The leading features of my design consist of the back or upright portion A; the arms or lateral portions B extending outwardly from the back A, and bed portion C, C', C². The portion A which constitutes the head board of the bed and back of the sofa, rises substantially vertically from the side portions D and is provided at the top with a panel or portion a which extends across the back in bas relief. The lateral portions B which stand out from each end of the back in substantially a horizontal direction, are apparently supported upon the side portions D by means of blocks or posts b and interposed between each of these lateral portions B and side portions D are upright rounds or bars b', which together with the portions B and b constitute and appear like arms to the sofa portion and side railings to the bed.

The section C of the bed portion is slightly less in width than the length of the side portions D, and the inner edge of the section C' abuts against the section C and extends slightly inward beyond the outer ends of, and

is apparently supported by such side portions D, while its outer edge as well as the inner 40 edge of the section C² is apparently supported by legs F at each end.

At the outer edge of the section C² are arranged depending portions G which apparently serve as supports for such section and 45 present the appearance of legs to the foot of the bed; and extending across the outer edge of the section C² is a strip H, which when viewed from the head portion A may be seen rising above the section C², and when viewed 50 from the other side in connection with the depending portions G, presents the appearance of an ordinary foot board having supporting legs.

Under the lower edges of each of the portions D, at a point substantially under the head board or back A, is a roller I which appears to hold the outer or rear ends of the side portions D aloof from the floor, while the inner ends of such side portions rest directly 60 upon the floor, the legs or portions F being also provided at their lower ends with rollers f upon which they apparently rest.

The upper surfaces of the sections C, C', C², are upholstered as shown to give the appearance 65 of a mattress.

Having thus described my design, what I claim, and desire to secure by Letters Patent, is—

The design for bed sofas or folding beds 70 substantially as herein shown and described.

CHAS. J. CONSER.
